(57) **CLAIM**

The ornamental design for a rear panel of an enclosure, as shown and described.

DESCRIPTION

FIG. 1 is a back, bottom, and left side perspective view of the rear panel of an enclosure, showing the new design;

FIG. 2 is a back, bottom, and right side perspective view thereof;

FIG. 3 is a back side elevational view thereof;

FIG. 4 is a bottom plan view thereof;

FIG. 5 is a top plan view thereof;

FIG. 6 is a left side elevational view thereof; and,

FIG. 7 is a right side elevational view thereof.

The broken lines represent unclaimed portions of the rear panel of an enclosure and form no part of the claimed design.
